(21) Appl. No.: **29/170,733**

(57) **CLAIM**

(22) Filed: **Nov. 12, 2002**

The ornamental design for a tourniquet pressure control apparatus, as shown and described.

(51) LOC (7) Cl. **24-01**

DESCRIPTION

(52) U.S. Cl. **D24/169**

FIG. 1 is a top right perspective view of a tourniquet pressure control apparatus plate according to the present design.

(58) Field of Search **D24/169; 600/485, 600/488, 494; 606/201, 202, 203**

FIG. 2 is a right side elevational view thereof.

(56) **References Cited**

FIG. 3 is a top left perspective view thereof.

U.S. PATENT DOCUMENTS

FIG. 4 is a left side elevational view thereof.
